DESIGN FOR A MATZO

Irving Streit, New York, N. Y.

Application January 11, 1939, Serial No. 82,276

Term of patent 14 years

To all whom it may concern:

Be it known that I, Irving Streit, a citizen of the United States and a resident of the city of New York, in the county of New York and State of New York, have invented a new, original, and ornamental Design for Matzos, of which the following is a specification, reference being had to the accompanying drawing, constituting a part thereof.

The figure is a plan view of the matzo showing my new design.

The matzos are of usual thickness of about one-eighth inch and the opposite side is of the usual appearance having horizontal perforations spaced approximately one-fourth of an inch apart.

I claim:

The ornamental design for a matzo, substantially as shown and described.

IRVING STREIT.
